TRAFFIC SIGNAL DEVICE

Joe Turano, Sacramento, Calif.

Application July 21, 1936, Serial No. 91,757

1 Claim. (Cl. 40—132)

This invention relates to certain new and useful improvements in traffic signal devices.

The primary object of the invention is to provide a traffic signal device in the form of an illuminated box or casing having a transparent front wall and designed to be carried by automobiles or placed at curves on highways and at railroad crossings with safety signal indicia on the transparent wall for warning motorists and 10 pedestrians of the danger of reckless driving.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a front elevational view of a traffic signal device constructed in accordance with the 20 present invention showing the safety first indicia painted or otherwise impressed upon the transparent front wall of the illuminated casing;

Figure 2 is a horizontal longitudinal sectional view taken on line 2—2 of Figure 1, showing the 25 illuminated casing structure of the traffic signal device;

Figure 3 is a vertical detail cross-sectional view taken on line 3—3 of Figure 1, and Figure 4 is a 30 detail sectional view of a corner of the casing showing the manner of securing the front glass plate in position.

The traffic signal device comprises a casing, preferably of rectangular formation and having a rear wall 5, end walls 6 and top and bottom walls 35 7, the open front side of the casing being closed by a transparent glass plate 8. To facilitate the mounting of the traffic signal device upon an automobile or for placement at curves on highways or at railroad crossings, a bracket plate 9 40 is secured to the rear wall 5 of the casing and projects below the casing as illustrated in Figure 1.

A reflector is housed within the casing and includes a central flat portion 10a anchored to the inner face of the rear wall 5 with curved portions 10 directed forwardly toward the front side of the casing as illustrated.

The mounting for the transparent glass plate 8 includes a rectangular frame 11, angular in cross-section to provide a front strip 12 and a side 50 flange 13. Bendable clips 14 are carried by the frame 11 and are adapted to be bent over the edges of the glass plate 8 as shown more clearly in Figure 3 at the inner side of the glass plate while a gasket 15 is interposed between the glass plate 55 and the front strip 12 of the frame 11. To retain

the glass plate and holding frame therefor in position at the open front side of the casing, and to reduce the number of points of contact between the casing and glass plate, an apertured inwardly directed struck-out lug 16 is carried by each end wall 6 of the casing intermediate the upper and lower ends thereof and a block 17 of substantially the same size as said lug and having a threaded opening therein is soldered or otherwise secured to the forward side of each lug 16. 10 As the lug 16 struck-out from the wall 6 of the casing is formed of relatively thin gauge metal, it would be impracticable to form threads in an opening therein and for this reason, the block 17 that constitutes a nut, is carried by said lug. 15 A screw 18 passes through the front strip 12 of the rectangular frame and also through a relatively narrow cut-out notch 8a in the edge of the glass plate 8 for threaded passage through the block 17 and free passage through the apertured 20 lug 16, a washer 19 being interposed between the head of the screw 18 and the front strip 12. The block 17 extends above and below the notch 8a and bears against the inner surface of the glass 25 plate 8 is therefore held between the front strip 12 of the holding frame and the clips 14, the holding frame providing the sole support for the glass plate 8. From an inspection of Figure 4, it will be seen that the block 17 is engaged with the 30 inner side of the glass plate 8 at opposite sides of the cut-out notch 8a. It will also be observed that the lug 16 is struck-out from the front end of the end wall 6 of the casing and that the forward edges of the end wall at the opposite sides 35 of the opening resulting from the struck-out lug 16 are engaged with the front strip 12 of the holding frame.

A lamp socket 20 is centrally secured in the rear wall 5 of the casing for the mounting of a 40 lamp 21 within the casing and for communication with an electric conductor exteriorly of the casing.

As shown in Figure 1, the glass plate 8 at the forward side of the casing has traffic signals or 45 warnings as indicated by the reference character 22 that are printed or otherwise impressed thereon and are of such character as to promote safe driving, other illustrations denoted by the reference character 23 depicting the causes of accidents and for the purpose of instilling the idea of safe driving in the minds of automobile drivers. 50

While there is herein shown and described the preferred embodiment of the invention, it is nevertheless to be understood that minor changes 55

may be made therein without departing from the spirit and scope of the invention as claimed.

I claim:—

5 In a traffic signal device, a rectangular illuminated casing open at one side, a glass plate closure for the open side, said plate having traffic signal indicia and symbols imprinted thereon, the mounting for the glass plate including a rectangular frame having a front strip overlying the front of the glass plate and a side flange overlying the edge of the glass plate and sides of the casing, a gasket strip interposed between the front strip of the frame and the glass plate, inwardly

directed apertured lugs carried by the forward edges of the opposite ends of the casing, a block having a threaded opening therein, anchored to the outer face of each lug with the threaded opening therein registering with the apertures in the lugs and screws passing through the front strip and lugs and threaded through the blocks for securing the frame and glass plate in position on the casing, the side edges of the casing having abutting engagement with the front strip of the 10 rectangular frame. 5

JOE TURANO.
